UNITED STATES PATENT OFFICE.

LOUIS A. SCHMIDT, OF BROOKLYN, NEW YORK, ASSIGNOR TO R. HOE & CO., INC., OF NEW YORK, N. Y., A CORPORATION OF NEW YORK.

WEB GUIDE FOR ROTARY PRINTING MACHINES.

Application filed April 8, 1925. Serial No. 21,456.

This invention relates to certain improvements in web leading devices for rotary printing machines.

In rotary web printing machines, particularly multi-couple machines, the web, for the printing operation, has to be led or threaded between the form and the impression cylinders of the printing couples. To get the web through the couples, it is necessary that the couples be rotated, and while the threading speed is low the pressman has to get his fingers or his arms closely adjacent the bite of the cylinders to get the web through. This frequently results in injuries to the hands or arms of the pressman.

It is the especial object of the present invention to provide a simple and efficient construction for assisting in threading the web through the printing couples of a rotary printing machine, the construction being such that the web may be shoved or pushed into the bite of the cylinders so that it is unnecessary for the pressman to get his fingers between the cylinders, thus preventing injuries to the hands or arms of the pressman, which are very liable to happen where the pressman has to get his fingers into or close to the bite of the cylinders.

With this and other objects not specifically referred to, the invention consists in certain novel parts, arrangements and combinations which will be fully described in connection with the accompanying drawings and the novel features pointed out in the claims hereunto annexed.

In these drawings.—

Figure 1 is an end elevation, partly broken away and partly in section, of a multi-couple rotary web machine showing the invention, the view being more or less diagrammatic, and

Figure 2 is a side view, partly broken away, taken on the line 2—2 of Fig. 1 looking in the direction of the arrow.

While the invention is shown as illustrated in connection with a machine embodying a printing and perfecting couple, it will, of course, be understood that it will be used in a multi-couple machine or any single-couple machine where necessary or desired. In the machine illustrated there is provided a printing couple including a form cylinder 1 and an impression cylinder 2, these cylinders being mounted as usual on shafts 3 supported in side frames 4 of the machine. The

form cylinder 1 is inked from a distributor 5 and the usual distributing rolls 6. In the machine illustrated there is also provided a perfecting couple including a form cylinder 7 and an impression cylinder 8 supported on shafts 9 taking bearing in the side frames of the machine, the form cylinder 7 being inked from a distributor 10 and distributing rolls 11, as is usual.

The web W is led over the usual web guiding roll 12 to and between the cylinders 1, 2 of the first printing couple. In accordance with the invention a web support is provided on which the pressman may lay the end of the web and push it into the bite of the cylinders, which, as before stated, are turning very slowly and which act to seize the web and draw it onward. While this web support or guide may assume various forms, in the particular construction illustrated this support is in the form of a plate 13 of metal or other suitable material having a smooth surface so that the web can be readily pushed along it. This plate is mounted below one of the cylinders, as the impression cylinder 2, and is supported on arms 14 carried on a shaft 15 supported from brackets 16 secured to the side frames 4 of the machine, before referred to. This plate, as shown, extends a sufficient distance beyond the leading-in side of the cylinders so that the web may be conveniently placed thereon. The other end of this plate extends toward the impression or contact point of the cylinders and within their peripheries, the plate thus extending a sufficient distance so that the web is readily pushed into the bite of the cylinders, and in the best constructions this end of the plate is curved, as indicated at 17.

With this construction it is apparent that the pressman may take the web and push it up the smooth surface of the plate until it is taken by the cylinders, and at no time is it necessary for him to get his hands or arms anywhere near the contact point of the cylinders, the directing of the web being effected from a point well beyond the first cylinder of the couple. Accidents are, therefore, largely eliminated and at the same time the press is easily and quickly threaded.

While a convenient construction for effecting the invention is that illustrated, it will be understood, of course, that certain changes may be made in the shape and ar-

angement of the plate supports without departing from the scope of the invention as defined in the appended claims.

What I claim is:

- 5 1. In a printing machine, the combination of a printing couple including a form cylinder and an impression cylinder arranged for impression contact on a web, and a web guard and guide over which the web may be pushed by hand for web threading, said guard including a plate extending to one side of one of the cylinders on which the operator may lay his hands when moving the web for threading, the plate extending on the other side toward and between the peripheries of the form and impression cylinders, so that the operator may start the web into the bite of the form and impression cylinders at a point away from the contact point of the cylinders.
- 10 2. In a printing machine, the combination of a printing couple including a form cylinder and an impression cylinder arranged for impression contact on a web, and a web guide and guard located below one of the cylinders and having a web receiving sur-

face extending substantially the width of the cylinder at one side thereof on which the operator may lay his hands for pushing the web into the bite of the cylinders, the guide on its other side projecting between the peripheries of the cylinders, so that an operator may thread the web into the bite of the cylinders at a point distant from the point of impression contact of the cylinders.

3. In a printing machine, the combination of a printing couple, including a form cylinder and an impression cylinder arranged for impression contact on a web a web guide, a guide and guard plate located below the cylinders, on which the end of a web may be pushed or shoved into the bite of the cylinders, said plate extending widthwise of the cylinders having a curved end projecting toward the contact points of the cylinders and inside the peripheries thereof, so that the operator may thread the web into the bite of the cylinders at a point away from the point of impression contact.

In testimony whereof, I have hereunto set my hand.

LOUIS A. SCHMIDT.
